BEAT OSCILLATOR

Elmer Olson, Pomeroy, Iowa

Application February 17, 1941, Serial No. 379,219

1 Claim. (Cl. 250—36)

The principal object of this invention is to provide a tuned grid beat oscillator for accurately calibrating radio sets or other tuned electrical apparatuses.

A further object of this invention is to provide a beat oscillator circuit which will radiate a tuned frequency beat on any pre-selected frequency for setting or locating station frequencies and for adjusting trimmer condensers, push button tuning controls or the like of a radio set.

A still further object of this invention is to provide an oscillator of the tuned grid type which can be set at a desired frequency and which will, when a radio set is tuned to the principal harmonic of the frequency, give a visual signal to indicate the resonance of the respective circuits relative to each other.

A still further object of this invention is to provide a beat oscillator circuit which is extremely economical in manufacture, durable and efficient in use.

These and other objects will be apparent to those skilled in the art.

My invention consists in the construction, arrangement and combination of the various parts of the device, whereby the objects contemplated are attained as hereinafter more fully set forth, pointed out in my claim and illustrated in the accompanying drawing, in which:

The figure is a diagrammatic view of the circuit employed in my beat oscillator or frequency meter.

It has heretofore been difficult to set the push buttons of a radio unless the actual broadcasting station to be selected is tuned in, and even then it is difficult to hit the period of resonance of the carrier wave that is in exact tune with the station. Some attempts have been made to do this by the use of an ordinary wave meter, but this is difficult due to the broadness of the carrier of such mechanisms and the fact that the wave meter must have its antenna pick-up changed for each frequency variation. Furthermore, such frequency beat meters relied upon an audible signal rather than a visual indicator, were extremely critical as to their own inherent adjustment. I have overcome such disadvantages as will be appreciated and as will be hereinafter more fully set forth.

I have used the numeral 10 to indicate an ordinary triode type of vacuum tube having the ordinary plate element 11, grid 12 and filament 13. One side of the filament element is connected to the center tap of a battery or like 14, and the other side is connected to one of the 55

outer lead wires of the battery 14. Imposed in this last mentioned lead line is a switch 15 and rheostat 16. The other end of the battery 14 is connected through the medium of an electric lead line 17 with one side of a milliammeter 18. The numeral 19 indicates the primary windings of a coil having one end in electrical communication with the plate 11 and its other end in communication through a lead line 20 with the other side of the milliammeter 18. The numeral 21 indicates a condenser placed in multiple or shunted across the two terminals of the milliammeter 18. The secondary winding of the coil I have designated by the numeral 22, which is shunted by a variable condenser 23 as shown in the drawing. The upper end of this coil 22 is connected to one side of a condenser unit 24 and the other side of the condenser 24 is connected, through the medium of an electric lead line 25, with the grid 12 of the tube 10. The lower end of the coil 22 is connected to the central tap of the battery 14. The antenna plate 26 is connected into the circuit including the grid 12, variable condenser 23, and coil 22 as appears clearly in the drawing. The numeral 27 indicates an electric lead line having one of its ends in electrical communication with the lead line 25 and its other end designed to be secured to the control grid of a radio or like.

30 The practical operation of my device is as follows:

The complete unit is placed at a distance from the radio set to be tuned and the filament switch 15 is closed, thereby activating the filament 13 of the vacuum tube 10. The variable condenser is tuned to the frequency desired and calibrated for that frequency. This causes the vacuum tube 10 to oscillate at a certain frequency, thereby registering a definite beat on the milliammeter 18. The radio set is then tuned until the highest frequency of beat is indicated by the milliammeter, at which time the radio receiving set will be in resonance with the frequency determined on the condenser unit 23. Inasmuch as all of the various frequencies can be calibrated on the control shaft or dial of the condenser 23, it is merely necessary to set this condenser at any desired frequency such as one thousand kilocycles, twelve hundred kilocycles or the like, and then tune the radio receiving apparatus until the highest frequency of beat is noted on the milliammeter 18. The set can then be adjusted and will be accurately in tune for the frequency so determined. In some instances, it is necessary to connect the wire 27 to a control grid of the

radio set in order to intensify the reading of the milliammeter and the frequency of its beat. Thus it is possible to trace the operation of the radio set over its entire frequency band to determine the correct calibration point on the radio set for pre-setting automatic push buttons or other controls thereon. Thus it will be seen that I have provided a beat oscillator for use in tuning radio receiving apparatuses which fulfills all of my objects and presents many more obvious advantages. Its extreme simplicity of operation makes it a highly desirable instrument for use in setting automatic push button controls on modern radio apparatuses, and the equipment can be made in a small compact form and gives a visual signal indicating the period of resonance of the receiver relative to the frequency set on my device.

Some changes may be made in the construction and arrangement of my improved beat oscillator without departing from the real spirit and pur-

pose of my invention, and it is my intention to cover by my claim any modified forms of structure or use of mechanical equivalents which may be reasonably included within their scope.

5 I claim:

In a tuning oscillator, a triode tube, a source of electrical energy for energizing the filament of said tube, a tuning coil having its secondary circuit imposed between the grid of said tube and one of its filament connections, an antenna plate secured to said last mentioned filament connection, a calibrated tuning condenser shunted across said secondary of said tuning grid, a milliammeter having one of its terminals in communication with a source of electrical energy and its other side in communication with the primary winding of said tuning grid, and an electric lead line in communication with the other side of said primary coil and the plate of said tube.

ELMER OLSON.
